UNITED STATES PATENT OFFICE.

GEORGE A. KNAAK, OF MILWAUKEE, WISCONSIN.

DESIGN FOR A CONTROLLER.

55,620.

Specification for Design.

Patented July 6, 1920.

Application filed November 28, 1919. Serial No. 341,319. Term of patent 14 years.

To all whom it may concern:

Be it known that I, GEORGE A. KNAAK, a citizen of the United States, residing at the city of Milwaukee, in the county of Milwaukee and State of Wisconsin, have invented a new, original, and ornamental Design for a Controller, of which the following is a specification, reference being had to the accompanying drawings, forming a part hereof.

Figure 1 is a side elevation; Fig. 2 is a

plan view; Fig. 3 is an elevation of one end; and Fig. 4 is an elevation of the other end of a controller embodying my new, original and ornamental design.

I claim:

The ornamental design for a controller substantially as shown.

In witness whereof I hereto affix my signature.

GEORGE A. KNAAK.
